CLAIM

The ornamental design for embolization microcatheter for delivery of beads to peripheral vessels as shown and described.

DESCRIPTION

FIG. 1 is a front perspective view of an embolization microcatheter for delivery of beads to peripheral vessels in accordance with the new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is an enlarged left side view taken from FIG. 4.

The broken lines in the drawings illustrate portions of the embolization microcatheter for delivery of beads to peripheral vessels and form no part of the claims design.

(Continued)

The break lines in FIGS. 1-7 indicate that the appearance of any portion of the embolization microcatheter for delivery of beads to peripheral vessels between the break lines forms no part of the claimed design.

1 Claim, 8 Drawing Sheets
